[57] CLAIM

The ornamental design for a gas barbecue grill, as shown and described.

DESCRIPTION

FIG. 1 is a front perspective view of a gas barbecue grill showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and

FIG. 7 is a right side elevational view thereof.

The gas tank shown in broken lines in FIGS. 1-3 and 5-7 is shown for illustrative purposes only and forms no part of the claimed design.

FIG. 1.

FIG. 2.

FIG. 3.

FIG. 4.

FIG. 5.

FIG. 6.

FIG. 7.
